UNITED STATES PATENT OFFICE.

LOUIS VINCENT FOSCATO, OF BAYSIDE, NEW YORK, ASSIGNOR TO V. FOSCATO, INC., OF NEW YORK, N. Y., A CORPORATION OF NEW YORK.

TERAZZO FLOORING.

Application filed August 30, 1922. Serial No. 585,196.

To all whom it may concern:

Be it known that I, LOUIS VINCENT FOSCATO, a citizen of the United States of America, residing in Bayside, in the county 5 of Queens and State of New York, have invented certain new and useful Improvements in Terazzo Flooring, of which the following is a specification.

This invention relates to composition 10 flooring, particularly of what is known as the terazzo types, that is to say, flooring which comprises a foundation bed usually of cement, and a superposed layer composed of small pieces of marble united together 15 with a suitable bond. In laying such floorings, it is well understood that the underlying support is frequently not strictly level, and it is, therefore, necessary in laying the foundation of cement to accurately level 20 the top surface of the cement bed. By this means a level layer of terazzo can be superposed upon the cement bed without the necessity of varying the thickness of the terazzo. It has also heretofore been pro- 25 posed to provide separate strips (usually of brass), by means of which the terazzo is laid in panels or blocks both for the purpose of localizing any possible cracking of the terazzo, and also for the purpose of introducing pleasing designs into the flooring. Such strips have heretofore been constructed so that their top edges constitute a leveling gauge, so as to facilitate the laying of 30 the terazzo body.

35 My invention includes a novel form of strip which can be very easily and cheaply manufactured.

In the drawings, wherein I have illustrated one form of the invention,

40 Figure 1 is a cross-section of the flooring made according to the present invention.

Fig. 2 may be regarded as a plan of Fig. 1.

Fig. 3 illustrates the construction and operation of the means for embedding or inserting the strips.

Referring first to Fig. 1—let A indicate any suitable body of cement or other foundation, the upper edge B of which is levelled by a suitable means when the cement is being laid. C indicates the layer of terazzo or other similar flooring. D is my improved levelling and separating strip which is best constructed of brass or other non-oxidizable metal. The member D is of any appropriate 50 length and shape to divide the flooring into

panels or sections, as shown in Fig. 2, for instance. Usually the strips are laid straight and the panels are rectangular in form. The strip D best comprises a narrow sheet of brass having at suitable intervals triangular 60 projections E struck outwardly from the body of the metal, it being preferred to arrange these projections in pairs, and to extend adjacent pairs from opposite sides of the strip. When the projections are bent 65 outwardly, they preferably extend at right angles to the body of the strip, and their upper edges are straight, or in other words, perpendicular to the side of the strip. Their lower edges are bevelled or inclined, joining 70 the strip near the lower edge of the latter. This construction enables the strip to be inserted in the cement foundation with the least disturbance of the latter and with the greatest amount of facility. It will be 75 understood that the strips are not inserted until the cement has become somewhat set, and therefore, resists the embedding of the strips to a considerable degree.

The upper edges F of the projections E 80 constitute levelling means, so that if the strip is inserted to a point where the edges F are at the same level with the upper surface of the concrete foundation, the operator is assured that the strip has penetrated to the 85 right degree, and that the upper edge F of the entire strip is level. The cutting of the projections from the body of the metal leaves apertures H H triangular in shape, into which the concrete flows, thus forming 90 a bond or anchor, tending to preserve the strips in their initial position, which tendency becomes positive when the concrete has become hard.

In laying such strips, I make use of the 95 device shown in Fig. 3, which comprises a strip of wood or other suitable material J, having secured to its upper face and one side face an angle-iron K, the vertical side L of the angle iron being spaced apart from the 100 strip J a sufficient distance to insert the top of the strip D. Preferably a lining strip M is also provided, so that in use the laying device is not materially affected by wear. Preferably between the lining strip M and 105 the side L of the angle-iron I introduce a strip N, the lower side of which not only provides a means for spacing the side L and strip M apart, so that the space thus formed snugly receives the upper edge of the strip 110

D, but also serves as an abutment for limiting the insertion of the strip D in the member K. Preferably the side L of the angle-iron is of just sufficient depth, so that when 5 the top edge of the strip D contacts with the spacing strip N, the lower edge of the angle-iron will contact with the edges F of the projections E on one side of the strip D, while the lower edge of the lining member 10 M will contact with those on the opposite side of the strip D. In actual application the laying member K is fitted over the top of the strip, and the lower part of the strip pressed into the bed of concrete until the 15 bottom edge O of the laying member lies flat upon the upper surface of the concrete. This usually requires considerable force, as by the use of a hammer. Preferably the lower surface O of the member K is of more 20 extended area than the top, so as to provide a stop of considerable surface area which upon contactin~ with the upper surface of the concrete will tend to limit any further downward movement of the strip. When the 25 proper position is reached, the member K is removed, leaving the strip D embedded in the concrete, the member K being then used for the succeeding strips. If there has been any error on the part of the workman in 30 failing to sink the strip D sufficiently, the upper edges F of the projections E form an accurate gauge for further depression.

While I have shown and described several forms of the invention, it will be understood that I do not wish to be limited thereto, 35 since various changes may be made therein without departing from the spirit of the invention.

What I claim is:—

1. A levelling strip for terazzo floorings or the like, comprising a narrow sheet of metal having projections struck up from the body of the metal, said projections being substantially vertical and having substantially horizontal top edges. 45

2. A levelling strip for terazzo floorings or the like, comprising a narrow sheet of metal having projections struck up from the body of the metal, said projections being substantially vertical and having substantially horizontal top edges, and being 50 triangular in form.

3. A levelling strip for terazzo floorings or the like, comprising a narrow sheet of metal having projections struck up from the body of the metal, said projections being substantially vertical and having substantially horizontal top edges, and being triangular in form, and said projections extending on both sides of said metal sheet. 55

In witness whereof, I have hereunto signed my name.

LOUIS VINCENT FOSCATO.
